UNITED STATES PATENT OFFICE.

WILLIAM ROBINSON, OF BELLEFONTAINE, OHIO, ASSIGNOR OF ONE-HALF
TO WM. LANE, OF SAME PLACE.

CAR-COUPING.

SPECIFICATION forming part of Letters Patent No. 393,268, dated November 20, 1888.

Application filed February 27, 1888. Serial No. 265,416. (No model.)

To all whom it may concern:

Be it known that I, WILLIAM ROBINSON, of Bellefontaine, in the county of Logan and State of Ohio, have invented certain new and useful 5 Improvements in Automatic Car-Couplings; and I do hereby declare the following to be a full, clear, and exact description of the invention, such as will enable others skilled in the art to which it pertains to make and use it, 10 reference being had to the accompanying drawings, which form part of this specification.

My invention relates to an improvement in automatic car-couplings; and it consists in the combination of a buffer-head, which is recessed on its inner side, with a spring-actuated hook, which is pivoted in the recessed buffer-head, and which has a cam or projection formed upon its inner side for the projection on the operating-lever to strike against and 20 thus force the hooks apart to uncouple them, as will be more fully described hereinafter.

The object of my invention is to produce a car-coupling which can be used in connection with the usual link and pin, if so desired, but 25 which is automatic in its action, simple in construction, and always reliable.

Figure 1 is a plan view of a car-coupling embodying my invention. Fig. 2 is a detached view of the operating cross-rod. Fig. 30 3 is a perspective of a coupling embodying my invention.

A represents the buffer-head, which is recessed on its inner side to receive the pivoted hook B. Through the front end of the buffer-head and in the front end of the hook B is formed a suitable opening or recess, C, so that the ordinary link can be used in connection with a coupling of this kind. The coupling-pins, when links are used, are passed down 35 through the opening D, which extends through the front end of the buffer-head only. Each head is recessed, as here shown, so as to have the coupling-hook placed entirely within it, and thus protect the front ends of the hooks 40 when the cars run together, so as to prevent them from being crushed or broken. Bearing against one of the timbers of the cars at one end and against the rear end of the hook 45

at the other is a suitable spring, F, which keeps the front end of the hook always pressed 50 forward, ready to engage with a hook of another car, but which spring allows the front end of each hook to readily give backward when the cars run together, in order to allow the points of the hooks to pass each other. 55 Upon the outer edge of the hook is formed a cam or beveled projection, G, against which the beveled projection H upon the operating cross-rod I strikes, for the purpose of forcing the hook back into the recess in the head 60 and thus uncoupling it. The rod I is journaled upon the under side of the car and is provided with a handle, J, at each end. The projection H hangs downward below the buffer-heads until one of the handles is operated, 65 when this beveled projection H is forced downward, so as to strike against the cam or projection G upon the hook and force the front end of the hook backward into the recess in the head. 70

In order to prevent the buffer-heads from being moved laterally far enough to allow the hooks to become uncoupled, a guard, O, is secured to each car, as shown, and which is just sufficiently far removed from the buffer-head 75 to allow the end of the opposing buffer-head to freely enter. The hooks being held in position by means of the springs F, and the heads A being prevented from moving laterally by the guards, it is impossible for the 80 cars to become disconnected after they have once been coupled, unless the rod I is operated.

In case it is desired to operate the rod I from the top of a freight-car, a rod will be 85 made to extend up the side of the car in the usual manner, and which will be connected to one of the handles J. In case this coupling is to be applied to a passenger-car, a short lever will be pivoted upon the end of the car 90 and connected to the front end of the hook by a short connecting-rod, which passes through the outer side of the buffer-head.

This coupling being automatic, there is no necessity of the brakeman venturing between 95 cars, is cheap and simple in construction, is

positive in its operation, and dispenses with all necessity for brakemen to couple the cars together.

Having thus described my invention, I

5 claim—

The combination of a buffer-head recessed upon its inner side, with the spring-actuated pivoted hook placed in the recess and provided with a cam, G, the rod I, provided with

the beveled projection H, and the guard which is secured to the end of the car, substantially as described.

In testimony whereof I affix my signature in presence of two witnesses.

WILLIAM ROBINSON.
